TIME ZONE WATCH

Ira Guilden, Miami Beach, Fla., assignor, by
mesne assignments, to The First National Bank
of Boston, Boston, Mass., a corporation of the
United States of America, as trustee

Application June 5, 1945, Serial No. 597,605

8 Claims. (Cl. 58—43)

1

This invention relates to timepieces or chronometers, such as clocks, watches and the like, having an hour wheel driven by a motor mechanism, and its principal object is to provide a simple, efficient and reliable means for setting the hour hand forward or backward to correspond with a given time zone, without stopping or in any way disturbing the motor mechanism or the setting of the minute hand.

A further object is to provide an indicator, operative conjointly with an hour-hand setting mechanism, to designate the particular time zone for which the hour hand is set.

Other objects relate to various features of construction and will be apparent from a consideration of the following description and the accompanying drawings, wherein:

Fig. 1 is an enlarged face view of a wrist watch, with parts broken away and shown in section, embodying the present invention;

Fig. 2 is a vertical section through the wrist watch shown in Fig. 1;

Fig. 3 is a plan view of the setting mechanism and associated parts; and

Fig. 4 is a plan view of the slip-clutch connection between the hour wheel and index wheel which carries the hour hand.

In accordance with the present invention a timepiece such as a wrist watch, a clock operated either by a spring motor, a synchronous electric motor, an impulse motor or any other type of suitable motor mechanism, is provided with the usual hour wheel which may be driven either at a constant speed or intermittently to rotate one revolution every twelve or twenty-four hours, depending upon the graduation of the face of the watch or clock. The hour hand is connected to a rotatable disk, such as a ratchet or index wheel which is connected to the hour wheel by means constituting a slip-clutch connection operative normally to rotate the disk synchronously with the hour wheel and to permit the disk to be advanced or retracted, relative to the hour wheel, thereby to advance or retract the hour hand correspondingly without stopping or in any way interfering with the normal operation of the motor mechanism. The hour hand disk may be set or rotated by any suitable actuating mechanism such, for example, as a pawl or the like associated with an operating lever so designed that a single actuation is effective to cause the pawl to rotate the disk and hence the hour hand, relative to the hour wheel, through a predetermined angle, thereby changing the setting of the

2

hour hand by one hour or other predetermined time interval.

In addition I provide a rotatable indicator having visible portions containing indicia designating different time zones, connected with the aforesaid actuating mechanism so as to be simultaneously rotated or set to correspond with the setting of the hour hand. To this end the indicator may comprise a ratchet or index wheel which carries a dial showing the different time zones, the ratchet wheel being associated with a pawl or the like means actuated by the aforesaid operating lever for the hour hand so as to designate the particular time zone for which the hour hand is set.

The embodiment herein shown for the purpose of illustration is a navigation type wrist watch having the usual case center 1, movement 2, dial 3 and other conventional parts known to the art. The movement 2 comprises the usual spring motor, including the hour wheel 5 (Fig. 2) fixed to the cannon or spindle 6 which is driven at a constant speed to rotate one revolution every twelve hours.

The hub 8 of an index wheel 10 is rotatably mounted about the cannon 6 with its body portion spaced above the hour wheel 5. An arcuate recess 11 is formed in the body portion of the index wheel 10 and this recess terminates in an arcuate slot 12, as shown in Figs. 2 and 4. The periphery of the index 10 is formed with ratchet teeth 14, as shown more clearly in Fig. 4. One end of an arcuate-shaped leaf spring 15 is anchored by a rivet 16 in the recess 11 and the free end of the spring 15 extends inwardly through the slot 12 to a position contiguous to the upper face of the hour wheel 5. The body portion of the hour wheel 5 is formed with twelve circular openings or recesses 20, the centers of which are spaced 30° apart, and the free end of the spring 15 carries a button or the like protuberance 21 which is received in one of the openings 20 of the hour wheel. The button 21 is formed with a bevelled surface, as shown in Fig. 2, which is not only effective to hold the button properly centered in the hole 20, but also to provide a cam element operative to urge the end of the spring 15 outwardly so that the button 21 may readily be disengaged from its seat about one hole and snapped into engagement about another hole 20 when the index wheel 10 is rotated relative to the hour wheel 5. These parts thus provide a slip-clutch connection between the index wheel and hour wheel operative normally to drive the index wheel 10 synchronously with the hour

wheel 5 and permit the index wheel to be advanced or retracted, relative to the hour wheel, thereby to set the hour hand 24 (Fig. 2) carried by the hub 8. Since the openings 20 are spaced 30° apart, movement of the index wheel 10 carrying the button 21 from one hole to the next adjacent hole corresponds to a one-hour setting of the hand 24.

It will be observed that the rotation of the index wheel 10, relative to the hour wheel 5, to reset the hour hand does not stop or in any way interfere with the operation of the motor mechanism or movement 2; nor does it in any way affect the setting of the minute hand which is carried by a spindle or cannon 25 telescopically disposed within the cannon 6.

A dial disk index wheel 30 is mounted to rotate freely about the hub 8 of the index wheel 10, and the periphery of the wheel 30 is formed with ratchet teeth 31. The wheel 30 carries a dial index 32, the outer marginal portion of which is divided into twenty-four sectors having indicia designating the twenty-four international time zones. These zones are given numbers which correspond to the number of hours necessary to add or subtract in the particular zone in order to correct the Greenwich mean time, the zones to the east of Greenwich being denoted by negative numbers and those to the west of Greenwich being given positive numbers. The dial 3 is formed with a small window 34 (Fig. 2) through which one of the marked sectors of the dial index 32 may be seen. The wheel 30 is yieldingly held against rotation and normally locked in set position by engagement of the free end of a small leaf spring 35 with the teeth 31, the spring 35 being mounted on the outer face of the movement, as shown in Fig. 2.

It will be noted that the ratchet wheel 30 and dial index 32 are independently movable relative to both the ratchet wheel or index 10 and hour wheel 5, and hence the dial index 32 when being set may be moved through an angle different from that of the index wheel 10. Since it is generally desired to reset the hour hand by intervals of one hour, the angular movement of the index wheel 10 is 30°, whereas the corresponding movement of the dial index (with twenty-four international time zones) is 15°. Accordingly the dial 31 must be rotated through an angle of but 15° while the index wheel 10 is being rotated through an angle of 30°.

The operating mechanism herein shown for accomplishing the simultaneous setting of the index wheel and dial index comprises a generally triangular-shaped index lever 40, pivoted at 41 to the upper face of the movement 2, so as to swing back and forth within the recess portion 42 formed in the upper face of the movement. Detent members 44 and 45 are mounted on opposite portions on the inner end of the lever 40 and each of the detent members carries a pair of resilient members 46 and 47, the member 47 extending in opposite directions and being engageable with the teeth 31 of wheel 30, and the member 46 likewise extending in opposite directions and being engageable with the teeth 14 of index wheel 10. The design of the parts is such that when the lever 40 is in neutral or inactive position, as shown in Fig. 1, the detent and ratchet teeth are normally disengaged from each other, but when the lever 40 is rocked from neutral or inactive position in either a clockwise or counterclockwise direction, as indicated by the solid dot-and-dash lines of Fig. 3, the resilient members 46 and 47 of one of

the two detent members engage the ratchet teeth 14 and 31, respectively, and rotate the wheel 10 through an angle of 30° and the index 30 through an angle of 15°. When the lever 40 is retracted from active position to neutral position, the resilient members 46 and 47 of the active detent, due to their resiliency, slide back over the teeth 14 and 31 without moving the ratchet and index wheels since both are yieldingly held in set position by the button 21 and the spring 35, respectively, with sufficient force to overcome the tendency of the spring member of the detents to cause reverse movement.

Rocking movement of the index lever 40 is controlled through a link 50 pivotally secured adjacent to one end to the lever 40 and at its opposite end to a rocker arm 52 pivotally mounted at 53 within a recess or relief portion 54 at the inner periphery of the watch case 1. The opposite ends of the rocker arm 52 carry leaf springs 56, the free ends of which engage the inner periphery of the case so as normally to hold the rocker arm in a neutral or inactive position, as shown in Fig. 1. A pair of push buttons 60 and 61, received in openings formed in the case 1 and held in place by springs 62, provides the operating means for rocking the arm 52 in one direction or the other.

With the construction and arrangement of parts herein shown the push button 60 may be depressed to swing rocker arm 52 in a clockwise direction, which movement of the rocker arm is transmitted through link 50 to swing lever 40 in a counterclockwise direction, as indicated by the full lines of Fig. 3. The counterclockwise movement of lever 40 brings the spring member 46 and 47 of detent 44 into operation to rotate index wheel 10 through an angle of 30° in a clockwise direction, thereby setting the hour hand 24 ahead one hour, and simultaneously rotates dial index 30 through an angle of 15°, thereby effecting the corresponding change in the setting of the dial 32. Likewise, depression of button 61 causes a reverse movement of the hour hand and dial index. Thus, by simply depressing one of the buttons, the hour hand of the watch may be reset ahead or behind exactly one hour without interfering with the movement 2 or affecting the setting of the minute hand, and as the dial index is simultaneously set to indicate the particular time zone for which the hour hand is set, a mere glance at the face of the watch shows the exact time with reference to Greenwich mean time. By successively depressing one or the other of the push buttons, the hour hand and index dial may be set to indicate the exact time in any desired international time zone.

While I have shown and described one desirable embodiment of the invention, it is understood that this disclosure is for the purpose of illustration, and that various changes in shape, proportion and arrangement of parts, as well as the substitution of equivalent elements for those herein shown and described, may be made without departing from the spirit and scope of the invention as set forth in the appended claims.

I claim:

1. In a timepiece of the type having an hour wheel driven by a motor mechanism, an index disk rotatable about an axis concentric with said hour wheel, a slip-clutch connection between said index disk and hour wheel, said slip-clutch being operative normally to drive said index disk synchronously with said hour wheel and to permit said index disk to be advanced relative to said hour wheel, an hour hand carried by said index

disk, a rotatable dial having portions containing indicia designating different time zones, and setting means having parts engageable with said index disk and dial for advancing said index disk and dial through predetermined angles, thereby to change the setting of said hour hand by a predetermined time interval and simultaneously set the dial to correspond with the setting of said hour hand.

2. In a timepiece of the type having an hour wheel driven by a motor mechanism, a ratchet wheel concentrically mounted with respect to said hour wheel, a slip-clutch connection between said ratchet wheel and hour wheel, said slip-clutch being operative normally to drive said ratchet synchronously with said hour wheel and to permit said ratchet wheel to be advanced or retracted relative to said hour wheel, an hour hand connected to said ratchet wheel, a dial wheel having ratchet teeth on its periphery, and setting means including detents engageable with said ratchet wheel and said ratchet teeth, and means for operating said detents so as to advance or retract said hour disk by predetermined time intervals and simultaneously set said dial wheel to correspond with the setting of said hour hand.

3. In a timepiece of the type having an hour wheel driven by a motor mechanism, an index wheel rotatable about an axis concentric with said hour wheel, a resilient member carried by one of the wheels and normally engaging the other wheel to provide a slip-clutch connection normally operative to rotate the wheel synchronously and to permit the index wheel to be advanced relative to the hour wheel, an hour hand carried by said index wheel, a rotatable dial having portions containing indicia designating different time zones, and setting means having parts engageable with said index wheel and dial for advancing said index wheel and dial through predetermined angles, thereby to change the setting of said hour hand by a predetermined time interval and simultaneously set the dial to correspond with the setting of said hour hand.

4. In a timepiece of the type having an hour wheel driven by a motor mechanism, a ratchet wheel concentrically mounted with respect to said hour wheel, a slip-clutch connection between said ratchet wheel and hour wheel, said slip-clutch being operative normally to drive said ratchet wheel synchronously with said hour wheel and to permit said ratchet wheel to be advanced or retracted relative to said hour wheel, an hour hand connected to said ratchet wheel, a dial wheel having ratchet teeth on its periphery, and setting means comprising an index lever pivotally mounted to swing from an inactive position to an active position, a pair of detent members mounted on said lever and so arranged that one of the detent members engages said ratchet wheel and the other detent member engages the ratchet teeth of said dial to advance the ratchet wheel and dial through predetermined angles relative to said hour wheel in response to movement of said lever from inactive position to active position, a rocker arm for swinging said lever from inactive position to active position, and means for restoring and yieldingly holding the lever and rocker arm in inactive position.

5. In a timepiece of the type having an hour wheel driven by a motor mechanism, an index wheel rotatable about an axis concentric with said hour wheel, a resilient member carried by one of the wheels and normally engaging the other wheel to provide a slip-clutch connection

normally operative to rotate the wheels synchronously and to permit the index wheel to be advanced relative to the hour wheel, an indicator carried by said index wheel, a rotatable dial having portions containing indicia designating different time zones, and setting means for advancing said index wheel and dial through predetermined angles relative to said hour wheel, thereby to change the setting of said indicator by a predetermined time interval and simultaneously change the setting of said dial to correspond with the setting of said indicator, said means comprising an index lever pivotally mounted to swing from an inactive position to an active position, a pair of detents mounted on said lever and arranged to engage and advance said dial and index wheel through a predetermined angle relative to said hour wheel in response to movement of said lever from inactive position to active position, a rocker arm for swinging said lever from inactive position to active position, and means for restoring and yieldingly holding the lever and rocker arm in inactive position.

6. In a timepiece of the type having an hour wheel driven by a motor mechanism, an index wheel rotatable about an axis concentric with said hour wheel, a resilient member carried by one of the wheels and normally engaging the other wheel to provide a slip-clutch connection normally operative to rotate the wheel synchronously and to permit the index wheel to be advanced relative to the hour wheel, and hour hand carried by said index wheel, a rotatable dial having portions containing indicia designating different time zones, and setting means comprising an index lever pivotally mounted to swing from an inactive position to an active position, a pair of detent members mounted on said lever and so arranged that one of the detent members engages

40 said ratchet wheel and the other detent member engages the ratchet teeth of said dial to advance the ratchet wheel and dial through predetermined angles relative to said hour wheel in response to movement of said lever from inactive position to active position, a rocker arm for swinging said lever from inactive position to active position, and means for restoring and yieldingly holding the lever and rocker arm in inactive position.

7. In a timepiece of the type having an hour wheel driven by a motor mechanism, a ratchet wheel concentrically mounted with respect to said hour wheel, a slip-clutch connection between said ratchet wheel and hour wheel, said slip-clutch being operative normally to drive said ratchet wheel synchronously with said hour wheel and to permit said ratchet wheel to be advanced or retracted relative to said hour wheel, an indicator connected to said ratchet wheel, a dial having indicia designating different time zones, a pair of spaced opposed detents engageable with said ratchet wheel and dial, and means for selectively operating said detents to advance or retract said ratchet wheel and dial to change the setting of said indicator by a predetermined time interval, and simultaneously set the dial to correspond with the setting of said indicator.

8. In a timepiece of the type having an hour wheel driven by a motor mechanism, a ratchet wheel concentrically mounted with respect to said hour wheel, a slip-clutch connection between said ratchet wheel and hour wheel, said slip-clutch being operative normally to drive said ratchet wheel synchronously with said hour wheel and to permit said ratchet wheel to be advanced or re-

tracted relative to said hour wheel, an hour hand connected to said ratchet wheel, a dial wheel having ratchet teeth on its periphery, and setting means including a pair of spaced opposed detents, each having a pair of resilient members respectively engageable with said ratchet wheel and the ratchet teeth on said dial wheel, and means for selectively operating said detents simultaneously to advance or retract said ratchet wheel and dial wheel, thereby to change the setting of said hour hand by a predetermined time interval and to set the dial wheel to correspond with the setting of said hour hand.
